UNITED STATES PATENT OFFICE.

GROVER C. NEWLUN, OF COLVILLE, WASHINGTON.

WASTE-GAS-COLLECTING DEVICE.

1,277,997.

Specification of Letters Patent. Patented Sept. 3, 1918.

Application filed September 22, 1917. Serial No. 192,793.

To all whom it may concern:

Be it known that I, GROVER C. NEWLUN, a citizen of the United States, residing at Colville, in the county of Stevens, State of Washington, have invented a new and useful Waste-Gas-Collecting Device; and I do hereby declare the following to be a full, clear, and exact description of the invention, such as will enable others skilled in the art to which it appertains to make and use the same.

This invention relates to an improved waste charge or gas collecting device for internal combustion engines of automobiles.

In internal combustion engines it has been found that portions of the charge leak past the piston, particularly on the compression stroke of the piston and into the crank case, therefore, one of the objects of the invention is to provide an improved device for collecting and conveying the waste portions of the charge back to the carburetor, in order to mix with the subsequent charges.

A further object of the invention is the provision of means for permitting of an auxiliary supply of air to be drawn into and mixed with the waste portions of the charge on its course back to the carburetor.

A further object of the invention is to provide a simple, efficient and practical device of this kind consisting of few parts and which may be easily applied to automobile internal combustion engines without making any alterations in the structure of the engine.

In practical fields the details of construction may necessitate alteration falling within the scope of what is claimed.

The invention comprises further features and combination of parts as hereinafter set forth shown in the drawings and claimed.

In the drawings:

Figure 1 is a view of an internal combustion engine of an automobile, the hood of which automobile is in section in order to show the waste charge collecting device applied.

Fig. 2 is an enlarged detail perspective view of the waste charge collecting apparatus detached.

Fig. 3 is a sectional view on line 3—3 of Fig. 2.

Fig. 4 is a sectional view on line 4—4 of Fig. 3.

Fig. 5 is a sectional view on line 5—5 of Fig. 3.

Fig. 6 is a detail perspective view of the device or means for adjusting the tension of a spring of a valve for admitting air.

Referring more especially to the drawings 1 designates the hood of an automobile, 2 the radiator, and 3 the internal combustion engine, while 4 denotes the breather, which is patterned after the breather of the Ford automobile. The engine is provided with 60 the usual exhaust manifold 5, and the intake manifold 6, which is connected to the usual carburetor 7. One end of the casing of the carburetor is provided with a cylindrical nipple or extension 8, and by means 65 of a clamp 9 an upstanding tubular casing 10 is fastened to the breather 4. This clamp 9 consists of two sections 11 and 12, which are hingedly united as shown at 13. The section 11 of the clamp is integrally connected to the tubular casing 10 by means of the strap extension or bar 14. The free ends of the sections 11 and 12 terminate in ears 15, through which a thumb screw 16 extends, for clamping the sections of the clamp 70 about the exterior of the end portion of the breather 4. It is to be noted that the lower end of the tubular casing 10 fits telescopically into the breather, and the extension strap or bar 14 engages the upper edge of 75 the breather 4, thereby limiting the casing 10 into the breather. The tubular casing 10 has a laterally protruding tubular extension 16, in which a straining member 17 consisting of wire fabric is arranged. The 80 upper end of the casing 10 has a transverse disk wall 18 provided with perforations 19. A tubular guide 20 rises concentrically and upwardly from the wall 18, in which a valve stem 21 is guided. The lower 85 end of the stem carries a disk valve 22, to move toward and from the wall 18, for closing and opening the perforations 19. The upper end of the stem 21 is threaded, and mounted thereon are nuts 23 and 24, there 90 being a lock washer 25 between the two nuts. This washer is split as shown at 26, and has one of its ends 27 deflected, so as to bind against the nut 24, in order to lock

95

100

the nuts in their adjusted positions. A spring 27 is interposed between the nut 23 and the wall 18. The breather 4, it is to be noted, projects from the crank case of the engine and into which ease portions of the charges of the various cylinders waste. In other words portions of the charges leak past the pistons and into the crank case, and consequently when the pistons move on their suction strokes the waste portions of the charges are drawn through the breather into the casing 10. A tubular member 28, which may be rigid or flexible is fitted telescopically into the lateral tubular extension 16 of the casing 10, and is in turn fitted telescopically into the pipe or conduit 29. This pipe or tubular conduit 29 terminates in an elbow 30, the portion 31 of which is provided with a plurality of axially disposed extensions 32 and 33 of different diameters, either one of which is designed to telescope the nipple or extension 8 of the carbureter. The nipples or extensions similar to 8 of different carbureters vary in lengths and diameters, therefore the extensions 32 and 33 are constructed in different diameters, whereby various nipples may be fitted. Connected to an eye 34 of the elbow 30 is one end of a spring 35, the other end 30 of which is connected to an eye 36 of the exterior of the carbureter casing, said spring acting to hold the extension 33 in telescopic engagement with the nipple 8. Upon the suction strokes of the piston, a suction force is created in the tubular connections between the casing 10 and the carbureter casing, therefore, the waste portions of the charges, and an extra supply of air are drawn through the tubular connection and 49 into the carbureter casing, in order to mix with the charge in the carbureter. This extra supply of air is drawn into the casing 10 past the disk valve 22, since said valve opens responsive to the suction force created in said tubular connections 16, 28, 29 and 30. The disk wall 18 in addition to the apertures 19 is provided with the substantially semi-circular diametrically opposite

openings 37 and 38, in order to insure of a sufficient amount of air when the disk valve opens.

The invention having been set forth what is claimed as new and useful is:—

1. In combination with an internal combustion engine and a carbureter, a waste charge collecting device comprising a tubular casing carrying a clamp for securing said casing to the breather of the engine, said tubular casing having means to permit of an auxiliary supply of air thereto, and means of communication between the tubular casing and the carbureter casing, said means of communication comprising a lateral tubular extension integral with the tubular casing, a pipe having an elbow, said carbureter casing having a nipped opening to be telescopically engaged by said elbow, and a telescopic tubular connection between said pipe and said tubular extension.

2. In combination with an internal combustion engine and a carbureter, a waste charge collecting device comprising a tubular casing carrying a clamp for securing said casing to the breather of the engine, said tubular casing having means to permit of an auxiliary supply of air thereto, and means of communication between the tubular casing and the carbureter casing, said means of communication comprising a lateral tubular extension integral with the tubular casing, a pipe having an elbow, said carbureter casing having a nipped opening to be telescopically engaged by said elbow, and a telescopic tubular connection between said pipe and said tubular extension, and tensioning means connecting the elbow and the carbureter casing to hold the elbow in engagement with said nipped opening.

In testimony whereof I have signed my name to this specification in the presence of two subscribing witnesses.

GROVER C. NEWLUN.
